UNITED STATES PATENT OFFICE.

OSCAR W. CROPLEY, OF JUNIATA, NEBRASKA.

PAN AND JAR LIFTER.

1,215,253.

Specification of Letters Patent.

Patented Feb. 6, 1917.

Application filed January 13, 1916. Serial No. 71,951.

To all whom it may concern:

Be it known that I, OSCAR W. CROPLEY, a citizen of the United States, residing at Juniata, in the county of Adams and State of Nebraska, have invented certain new and useful Improvements in Pan and Jar Lifters, of which the following is a specification.

This invention relates to an improved lifter which may be used for handling hot pans or jars and the principal object of the invention is to provide a lifter so constructed that without adjustment it may be used for engaging either a deep or shallow pan and to also so construct it that it can be used for engaging a jar.

Another object of the invention is to so construct the holder that it may be formed almost entirely of resilient wire, a strip of sheet metal being provided for use in holding the jar.

Another object of the invention is to so construct the device that the two jaws will not readily get out of shape.

Another object of the invention is to provide a lifter of the character described which will be strong and durable and also to so construct it that it will be inexpensive to make thus permitting it to be placed upon the market at a relatively small cost.

30 This invention is illustrated in the accompanying drawings, wherein:—

Figure 1 is a top plan view showing the device used for engaging a jar.

Fig. 2 is a view showing the manner in which the device may be used for engaging a pan.

Fig. 3 is a view showing a different method of employing the device in connection with a pan.

40 Fig. 4 is a view in elevation of the improved holder.

The outer jaw 10 is formed from a single strand of resilient wire which is bent and doubled intermediate its length to provide the handle 11 and then twisted as shown at 12 to strengthen the handle and prevent the strands forming the side bars of the handle from spreading apart. After being twisted, the end portions of the wire are then bent to provide the rectangular outer jaw 10 and the extreme end portions of the wire are extended in overlapping relation as shown at 13 and terminate in hooks 14. The strip 15 which is preferably formed of flexible sheet metal but which may be formed of any suit-

able material has one end portion bent around the overlapping end portions 13 of the wire forming the outer jaw thus serving to connect the end portions of the wire. It should be noted that the side bars of the rectangular outer jaw 10 are bent as shown at 16 to provide additional resiliency and strength for the outer jaw and further that the extreme end portion of handle 11 is bent upwardly as shown at 17 to provide a hand grip by means of which the device can be easily held when applied as shown in Fig. 2.

The inner jaw 18 which is substantially U-shaped as shown in Fig. 4 fits within the outer jaw and is formed from a single strand of resilient wire bent to provide the handle 19 having its free end portion or bridge bent to form the hooks 20 for engaging the flange 21 of the pan 22 when the holder is used as shown in Fig. 2. The side arms of handle 19 are bent around the outer jaw as shown in Fig. 4 thus providing bearings 23 pivotally connecting the inner jaw with the outer jaw. The ends of the wire forming the inner jaw are twisted as shown at 24 and extend to provide the relatively short finger or spur 25 and the relatively long curved finger 26. This spur or finger 25 serves to engage the wall of the pan 22 when the device is used as shown in Fig. 3 and also serves to releasably connect the inner jaw with the free end portion of the gripping strip 15 by passing through one of the openings 27 formed in the free end portion of this strip. Therefore this flexible strip 15 can be tightly secured about a jar or pan 28 when it is desired to lift or tightly hold the jar.

When this device is in use it may be used either as shown in Figs. 1, 2 or 3. When used for engaging a jar, the flexible strip 15 is passed around the jar and the spur 25 is passed through one of the openings 27. The handles 11 and 19 can then be grasped and moved together to close the jaws of the device and tighten the strip around the jar. The jar will then be tightly held so that a cover can be easily removed or tightly put in place. Of course, this can also be used if it is desired to remove a pan or a jar from a pan of hot water or to remove the jar or a pan from an oven.

If this device is used as shown in Fig. 2, the flange 21 of the pan will be engaged upon opposite sides of the pan by means

of hooks 14 and 20. The handle 11 will then be grasped at the hand hold 17 and the pan can be easily lifted.

When used in the manner shown in Fig. 2, the device can be used for lifting either deep pans as shown or for lifting shallow pans such as pie pans. This device can also be used as shown in Fig. 3 for lifting a deep pan. When used as shown in this figure, the wall of the pan will be grasped by the two jaws 10 and 18, the jaw 18 engaging the inner face of the wall 22 and the jaw 10 engaging the outer face of the wall. It should be noted that when used in this manner, the bent portion 16 of the jaw 10 serves to provide space for the flange 21 as well as serving to give additional resiliency to the jaw. It should be further noted that the spur 25 engages the inner face of the pan wall and therefore a very tight grip can be obtained. The curved finger 26 is provided so that the strip 15 when placed about a jar will not be bent at right angles and therefore there will be no danger of this strip becoming broken by cracking due to bending and then straightening the strip.

I have therefore provided a kitchen implement or grapple as it might be termed which can be used either for removing shallow or deep pans from an oven or which can be used for holding a cylindrical object such as a can or fruit jar. It should be further noted that if desired to clean a lamp chimney or other object of a similar construction, the cleaning cloth can be engaged by the two jaws and the device then thrust into the lamp chimney carrying the cloth with it. The chimney can then be cleaned on the inside and the holder and cloth removed.

Copies of this patent may be obtained for five cents each, by addressing the "Commissioner of Patents, Washington, D. C."

What is claimed is:—

1. An implement of the character described comprising pivotally connected members, each having a handle and a jaw, one of said jaws being provided with side bars having their end portions extended in overlapping relation and terminating in engaging hooks, a flexible strip having one end portion secured about the overlapped end portions of the side bars of said jaw, the other of said jaws being provided with side bars having their end portions connected and extending to provide a spur and a guiding finger, the free end portion of said strip being provided with openings to receive said spur, and the handle of said last mentioned jaw being provided with a hook co-operating with the hooks of said first mentioned jaw. 60

2. An implement of the character described comprising pivotally connected members, each having a handle and a jaw, one of said jaws being provided with side bars having their end portions terminating in engaging hooks, a flexible strip having one end portion secured between the hooks of said jaw, the other of said jaws being provided with side bars having their end portions terminating in a spur and a guiding finger, the free end portion of said strip being provided with openings to receive said spur and the handle of said last mentioned jaw being provided with a hook co-operating with the hooks of the first mentioned jaw. 70

In testimony whereof I affix my signature in presence of two witnesses.

OSCAR W. CROPLEY.
